UNITED STATES PATENT OFFICE.

THOMAS H. PATERNALL, OF WILKINSBURG, PENNSYLVANIA, ASSIGNOR TO THE UNION SWITCH AND SIGNAL COMPANY, OF SWISSVALE, PENNSYLVANIA, A CORPORATION OF PENNSYLVANIA.

STAFF AND LEVER LOCK.

SPECIFICATION forming part of Letters Patent No. 743,325, dated November 3, 1903.

Application filed January 3, 1903. Serial No. 137,642. (No model.)

To all whom it may concern:

Be it known that I, THOMAS H. PATERNALL, of Wilkinsburg, in the county of Allegheny and State of Pennsylvania, have invented a new and useful Improvement in Staff and Lever Locks, of which the following is a full, clear, and exact description, reference being had to the accompanying drawings, in which—

Figure 1 is a front view representing the internal mechanism in dotted lines. Fig. 2 is a vertical section on the line II-II of Fig. 1. Fig. 3 is a longitudinal section on a large scale, representing the staff socket and support, a staff being represented in position to unlock the lever-lock. Figs. 4 and 5 are detail views of the staff-socket. Figs. 6 and 7 are side and end views of the operating-cam, respectively; and Figs. 8 and 9 are front and side views of the lever-lock.

My invention relates to staff and lever locking devices, and has for its object, in connection with a staff system, the control of the levers which are used to operate signals and switches and also the locking of the signal in its normal or danger position.

My invention consists in providing mechanism adapted to lock the signal or switch levers, which mechanism is operated by a staff which is used in the staff instrument forming a part of a system wherein the movement of trains is controlled by staff instruments which are electrically connected and operate in conjunction with each other, the instruments being locked and unlocked by staffs which can only be withdrawn and inserted under proper conditions for the safe operating of the trains, and this is described in my copending applications, Serial No. 101,716, filed April 7, 1902, and Serial No. 124,022, filed September 19, 1902.

My invention further consists in features of construction and combination of parts more fully hereinafter described, and pointed out in the claims.

In the drawings, 2 represents a frame or casing which incloses the operating parts of the device. This casing is secured to a suitable base or support 3. A locking-segment 4 is pivotally mounted in bearings 5, se-

cured to the base 3. The segment 4 is provided with ears 6, adapted to receive a pin 7, by which the signal-lever-operating rod 8 is secured to the segment.

The upper portion of the segment 4 engages the locking rod or bar 9, and its upper end 10' is guided by rollers 10 in such manner that the bar is capable of endwise movements. The locking-bar 9 also carries pins 11, which are insulated from the bar by a suitable bushing 12, and when in the normal locked position the opposite ends of the pin 11 make contact with contact-springs 13 and 14. These springs constitute the terminals of the circuit which connects one staff instrument with a distant staff instrument or instruments, and when the parts are in the position represented in the drawings the circuit is complete through pin 11 and contacts 13 and 14. The upper end of the locking rod or bar 10' is when the device is constructed as shown in the drawings made separate from the lower end and is connected thereto by a loose or slotted connection, a pin 16 being passed through the rod 10' and extended through the slots 17 in the locking-bar 9 in order to join the parts 9 10', so as to constitute one member of the locking mechanism, but permitting the segment 4 to be moved independently of the rods 9 10'. The rod 10' is also provided with a collar or pin 18, between which and the upper end of the locking-bar 9 is placed a coil-spring 19, arranged to hold the locking-bar 9 so that the pin 16 normally rests in the upper end of the slot.

In the upper portion of the frame or casing 2 is mounted a staff-socket 20, the front end of which is carried in an escutcheon 21, provided with a locking-tongue 22, which engages a longitudinal groove 36 in the staff 35 in inserting the staff within the socket, and when the staff is in its socket and is turned to operate the locking mechanism the tongue 22 will engage a transverse groove 37, as hereinafter described. The rear end of the socket is provided with a plug 23, having a rib 24 on its inner face and on its outer end a bearing portion 25, which is arranged to fit a bracket 26, secured to the casing 2. The

socket 20 is also provided with arms 27, in which is mounted a roller 28, adapted to engage a rocking cam 29, mounted upon a pin 30, secured to the casing 2. The cam 29 is provided with a lug or ear 31, to which is secured one end of a link 32. Its lower end is secured to the upper end of the locking-rod 10'. The socket 20 is also provided with depressions 20', which are engaged by a spring-pressed pin 33, by which the socket is held in the position in which it is placed after being rotated. The spring-pressed pin 33, which engages depressions 20', is readily disengaged when the staff-socket is turned by the operator rotating the staff, as the spring surrounding the pin 33 yields as the end of the pin is forced out of the depression.

A stop 34 is secured to the socket 20, and a coacting stop 34' is placed on the bracket 26, so as to limit its rotation.

The staff 35 is cylindrical and is provided with a longitudinal groove 36 and a transverse locking-groove 37, into which the groove 36 leads. The groove 37 when the staff 35 is in the socket, as shown in Fig. 3, is in registry with the tongue 22, and when the staff is turned to unlock the staff and lever lock the groove 37 prevents the withdrawal of the staff until the longitudinal groove 36 is brought in line with the tongue 22, as shown in Fig. 3. The inner end of the staff is provided with a slot 38, cut so as to register with the position of the rib 24 on the plug 23 with respect to the tongue 22 on the escutcheon 21. The relation of the rib 24 on the plug 23, secured in the end of the socket 20, bears to the tongue 22 on the escutcheon 21 determines whether the staff will operate the locking devices or not, for the notch or slot 38 is cut at an angle to the groove 36 in the same relation as the rib 24 bears to the tongue 22. Any variation between the grooves on the staff and the corresponding projection on the escutcheon and the socket-plug renders any staffs but the one designed to be used inoperative. By varying the relation of the rib 24 to the tongue 22 a large variety of combinations may be effected, the staffs being made to suit this relationship.

The operation to unlock the lever which controls the signal is as follows: The staff instruments at staff-stations and their signal lever-locks being in the normal condition—that is, the signal being displayed at "danger"—the electrical circuit between the stations is in the proper condition for an operator at a staff-station to ask the operator at a distant station to unlock his instrument, so as to permit him to withdraw a staff and permit a train to proceed to the next staff-station. Permission being given and the staff released a staff is withdrawn; but before it is given to the engineer it is placed in the socket 20, which operates lever-lock 9, and as it is turned so as to rotate the socket the roller 28 actuates the cam 29 and through the link 32 lifts the bar 10' and the locking-rod 9 free of the lever-segment 4, at the same time break-

ing the electric circuit at contacts 13 and 14 as the pin 11 is lifted out of contact therewith. This prevents further communication between the operators until the normal position of the lever-lock is restored. The locking rod and bar 9 is now in raised position. The segment may be turned and the signal or switch controlled by the lock may be operated. The staff 35 is then turned back. The spring on the locking-rod 10' and the slot in bar 9 afford a yielding connection which makes this possible. As the switch or signal is reversed this movement causes the locking-segment 4 to turn upon its pivot-pin 5, and as soon as its notched locking portion is reached the spring 19 expands and forces the locking-bar 9 automatically into locked engagement with segment 4. The staff is withdrawn from the lever-locking instrument and is delivered to the engine-man, and as soon as the train has passed the signal or switch must be reversed and again locked, because, as just described, the circuit is broken between the staff-stations, and the operators cannot communicate with each other until the pin 11 makes contact with the springs 13 and 14 and restores the electric circuits, and this can take place only when the lock is in its normal position and the signal is displayed at "danger."

The advantages of my invention will be appreciated by those familiar with the art, and this device affords a simple and effective means of preventing signals being left in the wrong position.

Many variations may be made by the skilled mechanic and electrician without departing from my invention.

What I claim is—

1. A lock for railway signals and switches, comprising an operating rod or connection, a locking member secured thereto, a second locking member arranged to engage directly with the other member, rotary staff-actuated mechanism connected to said second locking member, arranged to move the same out of locked engagement with the first, so as to permit movement of the operating rod or connection; substantially as described.

2. A staff and lever lock for railway signals and switches, comprising an operating rod or connection, a locking member secured thereto, a second endwise-movable locking member arranged to engage with the other member and retain the other member in locked position, a staff or key, and rotary cam mechanism adapted to be engaged by said staff or key, and connected to said second member, so as to move the same out of and into engagement with the other locking-piece, thereby releasing or locking the operating-rod; substantially as described.

3. A staff and lever lock for railway signals and switches, comprising an operating rod or connection, a pivoted locking member secured thereto, a second locking member arranged to engage with said pivoted member and retain the member in locked position, a staff or key,

and rotating mechanism adapted to be actuated by said staff or key and connected to said second member, so as to move the same out of and into engagement with the other locking-piece, thereby releasing or locking the operating-rod; substantially as described.

4. A staff and lever lock, comprising an operating-rod, a locking member secured thereto, a second member, arranged to engage therewith, a staff, a staff-socket for the staff, and connections between said socket and said second locking member, whereby it is operated when the staff is used to move the socket; substantially as described.

15 5. A staff and lever lock, comprising an operating-rod, a pivoted locking member, a second locking member arranged to engage therewith, a staff or key, a socket therefor, and a yielding actuating connection between said socket and said second locking member, so as to permit movement of the yielding connection without affecting the pivoted member when the staff-socket is moved by the rotation of the staff; substantially as described.

25 6. A staff and lever lock, comprising an operating-rod, a locking member, a second locking member arranged to engage therewith, a staff or key, a socket therefor, and a yielding actuating connection between said socket and said second locking member comprising a divided rod or bar united by a loose connection, so as to permit movement of the yielding connection without affecting the other member when the socket is turned by the staff or key; substantially as described.

35 7. A staff and lever lock, comprising an operating-rod, a locking member, a second locking member arranged to engage therewith, a staff or key, a rotatory socket therefor, and a yielding actuating connection between said socket and said second locking member, so as to permit movement of the yielding connection without affecting the other member; substantially as described.

45 8. A staff and lever lock, comprising an operating-rod, a locking member secured thereto, a second member, arranged to engage therewith, a staff, a socket for the staff and a detent for said socket, arranged to retain the socket and the locking mechanism in the position it is placed by the operator, and a connection between said socket and said second locking member, whereby it is operated; substantially as described.

55 9. A staff and lever lock, comprising an operating-rod, a locking member secured thereto, a second member, arranged to engage therewith, a staff, a socket for the staff, and stops to limit the movement of said socket, and a detent for said socket, arranged to re-

tain the socket and the locking mechanism in the position it is placed by the operator, and a connection between said socket and said second locking member, whereby it is operated; substantially as described.

65 10. A staff and lever lock for railway signals and switches, comprising an operating rod or connection, a locking member secured thereto, a second locking member arranged to engage with the other member, and retain the other member in locked position, a staff or key, and mechanism adapted to be engaged by said staff or key, connected to said second member, so as to move the same out of and into engagement with the other locking-piece, 75 a contact-piece carried by the second member, fixed contacts forming terminals for an electric circuit, said contact-piece closing the circuit through said fixed contacts when the parts are in locked position, and breaking 80 said contacts when the parts are in the unlocked position; substantially as described.

11. A staff and lever lock, comprising an operating-rod, a locking member secured thereto, a second member arranged to engage 85 therewith, a contact-piece carried thereby, fixed contacts forming terminals for an electric circuit, said contact-piece closing the circuit through said fixed contacts when the parts are in locked position, and breaking 90 said contacts when the parts are in the unlocked position, a staff, a socket for the staff, and connections between said socket and said second locking member, whereby the yielding connection being given an endwise movement 95 to effect the opening and closing of the circuit, and the engagement and disengagement with the second locking member; substantially as described.

12. A staff and lever lock, comprising an operating-rod, a locking member secured thereto, a second member arranged to engage therewith, a contact-piece carried thereby, fixed contacts forming terminals for an electric circuit, said contact-piece closing the circuit through said fixed contacts when the parts are in locked position, and breaking 100 said contacts when the parts are in the unlocked position, a staff, a rotatable socket for the staff, a loose connection between the said 105 socket and said second locking member whereby endwise movement is given thereto when the socket is rotated; substantially as described.

110 In testimony whereof I have hereunto set 115 my hand.

THOMAS H. PATENALL.
